THRUST-RELIEVED PROPELLER

Max M. Munk, Cottage City, Md.

Application July 23, 1937, Serial No. 155,328

9 Claims. (Cl. 170—168)

This invention relates to all kinds of screw-type fluid impellers, such as wind mills, office fans, and propellers, and particularly to aerial propellers. I will describe the invention in most 5 part as applied to the latter, the application to the other members of this class of impellers follows therefrom by analogy.

The invention consists in relieving the propeller from a portion of its axial airforce component, ordinarily called thrust, which has to be produced, by the provision of an airfoil or airfoils, preferably ring shaped airfoils in concentric relation to the propeller axis and positioned adjacent or not very far off the course 15 of the propeller blade tips. These airfoils, in keeping with the well known principles and practices of airfoil design, are so shaped and so inclined relative to the airflow attributable to the motion and rotation of the propeller, as to produce or experience an airforce component parallel and in the same direction as the propeller thrust, whereby the airfoil furnishes itself that portion of the total thrust by which the propeller has been relieved. With a stationary 20 propeller, this component may constitute the entire airforce of the several airfoil elements. With a traveling propeller, however, this condition entails that the airforce acting on each airfoil element is directed inwardly and forwardly.

30 The cross section of the airfoil shall be sharp trailed with gentle variations of its camber slope and of its wing section thickness, preferably thicker in front than in rear, and the leading edge or nose gently rounded. This leads to conventional modern efficient wing sections with inwardly directed suction side for aerial propellers, as with them the undisturbed airflow is almost straight. With stationary fans, this 35 may lead to extremely curved wing sections, as then the undisturbed streamlines are themselves strongly curved. The undisturbed air should impinge on the airfoil section of aerial propellers from the outside. This does not necessarily require an inwardly and conically directed zero-lift 40 line of the wing section, because the undisturbed airflow itself is converging. Hence, a wing section parallel to the axis is already inclined in the indicated manner relative to the undisturbed 45 propeller airflow.

The object of the invention is to provide for a propeller assembly having superior efficiency, lighter weight, smaller manufacturing costs, and above all a smaller propeller tip speed by virtue 50 of which the almost unbearable propeller noise of present day airplanes is reduced to a reasonable amount. For stationary airfoils are more efficient and less noisy than rapidly rotating propeller blades, and the thrust relief exerted by 55 the stationary airfoils makes it feasible to em-

ploy a propeller of smaller diameter and hence, at the same rotational speed, with smaller tip velocity than an unrelieved propeller would have, whereby the chief source of excessive noise is 5 eliminated.

These and other objects and advantages of the present invention will be described in the following specification and illustrated in the accompanying drawing, preferred embodiments being shown for illustration only, for, since the 10 very broad principles of my invention can be incorporated in many specific devices, it is not intended to be limited to the ones shown, except as such limitations are clearly imposed by the appended claims.

In the drawing, equal characters refer to similar parts throughout the several views, of which Fig. 1 shows an aerial propeller in sideview, with its relieving ring in cross section,

Fig. 2 shows the same propeller and ring assembly seen from the rear,

Fig. 3 is a diagram illustrating the determination of the zero lift direction of a wing section, and

Figs. 4 to 9 show the upper half of the propeller of Fig. 1 in the same view but somewhat 25 larger scale, and different types of relieving rings in cross section.

In Figs. 1 and 2 there is shown an engine housing 20 fixed to an airplane not shown in the drawing, an engine shaft 11, a four blade pusher propeller 10 mounted on shaft 11 having propeller tips 12, rods 21 mounted on engine housing 20, and an airfoil 30 the same being a closed circular ring and hence arched and looped. The 30 axis of ring 30 coincides with the axis of shaft 11. Arrow N represents the motion of the airplane relative to the air. Arrows L—M represent 35 schematically the motion of the air past the propeller disregarding the interference of ring 30, but taking into account the motion and the rotation of the propeller. Arrows L—M indicate 40 a converging flow. As shown in Fig. 4, ring 30 surrounds the propeller with suitable clearance. This has not to be particularly small, a reasonable 45 vicinity of ring 30 to the tip circle 12 is all that is required. It is also not material whether the ring is slightly in front of, co-planar with, or behind the propeller. The axial length of ring 30, the same being the chord length of its 50 wing section, is much smaller than the circumference of the ring, whereby the airfoil possesses a large aspect ratio, i. e. the circumferential span divided by the chord. The wing section of ring 30 is a so-called strut section, rounded at the 55 leading edge K, which is at the left of Fig. 4, and having a sharp trailing edge T. The thickness is gradually varying, and larger in front than in rear. The axis of wing section Fig. 4 is parallel to the propeller axis. The undis-

60

turbed airflow would have the direction such as L—M, and hence would impinge on the outside of the ring.

Figs. 5 to 8 differ from Fig. 4 by the wing sections of the ring only. In Fig. 5, the wing section is the same as in Fig. 4, except that the section axis is conically inclined, whereby the impinging angle relative to airflow L—M is increased. In Fig. 6 the wing section is unsymmetrical, the lower or pressure and less or even concavely curved camber line being on the outside. This ring is shown in front of the propeller plane, to illustrate another one of the several positions in which the rings will be effective. This position is not in direct relation to the wing section employed, but will be chiefly determined from general design considerations. Fig. 7 shows two rings in tandem relation, and Fig. 8 two in biplane relation, ring 34' surrounding ring 34, whereas ring 33 is in front of ring 33'. The inside diameter of rings 30, 31, 32 and 34 is larger than the propeller diameter of 10. The inside diameter of rings 33 and 33' is shown to be just slightly smaller than the diameter of propeller 10, the two rings 33 and 33' being in front and in rear respectively of the propeller. Biplane rings 34 and 34' illustrate the ring being located in rear of the propeller plane.

Fig. 9 illustrates a stationary propeller, such as an office fan. The undisturbed airflow of such propeller near its tips has the general character of curved line LM of Fig. 9. For that reason, a strongly curved wing section 35 is then in order, the rounded leading edge K outside.

In Fig. 3, a wing section is represented, having the leading edge K and the trailing edge T. For the purpose of the specification, the direction of the zero lift line G—T of any such section may be determined by connecting the trailing edge T with the center C of the section, the latter being determined by the conditions $DE=EF$, and $AC=BC$. GT represents the direction of the wing section for the purpose of this specification. The lift produced is directed broadly from L towards G, and more or less at right angles to LM.

With a wind mill, the airflow will be divergent, not convergent as in Fig. 1. The structural arrangement of Fig. 4 would not be suitable for a wind mill, because a divergent flow line LM would impinge on ring 30 from inside, not from outside as in Fig. 4. A divergent conical ring as in Fig. 5, or better as in Fig. 6, would be required.

In operation as an aerial propeller, the ring will relieve the propeller by a portion of the total thrust. At low speeds, before and during take-off, the portion by which the propeller is relieved will be considerably larger than at high speeds; but at these high speeds, less relief is necessary as the maximum thrust then available is anyhow, smaller than at low speeds. At these lower speeds, the relieving airfoil will also bring about that the propeller absorb more horsepower than without it, whereby the available power supply is utilized to better advantage.

I claim:

1. The combination of an aerial power-driven screw-type propeller and a stationary ring positioned adjacent the course of the propeller tips, said ring having a smooth, continuous, sharply trailed wing section contour, the zero-lift direction thereof being outwardly and rearwardly in-

clined relative to the direction of the propeller axis.

2. The combination of an aerial power-driven screw-type propeller and a plurality of stationary rings positioned adjacent the course of the propeller tips, said rings having a smooth, continuous, sharply trailed wing section contour, the zero-lift direction of the contour of at least one of said rings being outwardly and rearwardly inclined relative to the direction of the propeller axis.

3. The combination of a screw-type power driven fluid propeller and a stationary arch positioned adjacent the course of the propeller tips, said arch having a smooth continuous sharply trailed wing section contour the zero lift direction thereof being outwardly and rearwardly inclined relative to the flow produced by the propeller.

4. The combination of a screw-type power driven fluid propeller and a stationary ring positioned adjacent the course of the propeller tips, said ring having a smooth continuous sharply trailed wing section contour the zero lift direction thereof being outwardly and rearwardly inclined relative to the flow produced by the propeller.

5. The combination of a screw-type power driven propeller and a plurality of stationary rings positioned adjacent the course of the propeller tips, said rings having a smooth continuous sharply trailed wing section contour, the zero lift direction of at least the contour of one of said rings being outwardly and rearwardly inclined relative to the flow produced by the propeller.

6. The combination of an aerial propeller and a stationary large-aspect-ratio thrust relieving ring positioned adjacent the course of the propeller tips, having smooth, continuous sharply trailed wing section contours with their zero lift direction rearwardly and outwardly inclined relative to the air flow.

7. The combination of a power driven screw-type propeller and a stationary ring positioned adjacent the course of the propeller tips, said ring having a smooth, continuous sharply trailed cambered wing section contour, the zero lift direction thereof being outwardly and rearwardly inclined relative to the propeller axis and the mean camber being concave when viewed from outside the ring, convex when viewed from the axis.

8. The combination of a power driven screw-type propeller and a stationary ring positioned adjacent the course of the propeller tips, said ring having a smooth, continuous sharply trailed wing section contour, the zero lift direction thereof being outwardly and rearwardly inclined relative to the propeller axis, the maximum diameter of the ring being larger than the maximum propeller diameter.

9. The combination of a screw-type power driven fluid propeller and a stationary ring positioned adjacent the course of the propeller tips, said ring having a smooth continuous sharply trailed wing section contour, the line connecting the trailing edge of said contour with its center of section being outwardly and rearwardly inclined relative to the flow produced by the propeller.
